UNITED STATES PATENT OFFICE.

DAVID R. BOWEN, OF ANSONIA, CONNECTICUT, ASSIGNOR TO FARREL FOUNDRY AND MACHINE COMPANY, OF ANSONIA, CONNECTICUT, A CORPORATION OF CONNECTICUT.

PRESSURE-REGULATING DEVICE FOR ROLLER-MILLS.

974,349.

Specification of Letters Patent.

Patented Nov. 1, 1910.

Application filed March 23, 1910. Serial No. 551,203.

To all whom it may concern:

Be it known that I, DAVID R. BOWEN, a citizen of the United States, residing at Ansonia, county of New Haven, and State of Connecticut, have invented certain new and useful Improvements in Pressure-Regulating Devices for Roller-Mills, fully described and represented in the following specification and the accompanying drawings, forming a part of the same.

This invention relates to certain improvements in pressure regulating devices for roller mills.

In roller mills, and particularly such mills as are used for crushing cane, and similar substances, it is important that the rolls maintain the same pressure on the material passing between them irrespective of variations in the amount of the material. In such mills, therefore, it is customary to employ pressure regulating devices for the rolls, which include a hydraulic cylinder and ram, the cylinder being connected with a suitable hydraulic regulator, and the ram being arranged to bear on the roll bearing. A packing is, of course, necessary, in such constructions, between the ram and the interior of the hydraulic cylinder, to form a tight joint between the two. Experience has shown, however, that packing is unreliable, for the reason that its life is uncertain and varies widely. A packing may last for some weeks and it may give out in an hour or even less. When a packing gives out, the mill must be stopped and the packing renewed. The pressure regulating devices heretofore employed in roller mills include caps bolted to the supports or housings in which the bearings for the rolls are located. Each of these caps is bored or chambered and a ram is located in the bore, so that the wall of the bore in the cap forms the hydraulic cylinder for the ram, the ram thus working directly in a hydraulic cylinder integral with the cap. This bore or chamber is closed by a removable cover or plate secured by bolts to the top of the cap, this plate being perforated to provide for connections from the hydraulic regulator to the interior of the cylinder. It will be understood that the pressures which mills such as those referred

to develop are very heavy—in some instances, five hundred tons—and it is apparent that the cap and regulating construction must be exceedingly massive in order to 55 withstand such pressures. In the construction which has been referred to, the cover plate for the opening in the cap which forms the hydraulic cylinder is secured in place by heavy bolts or screw studs, and, in order to 60 withstand the forces developed, a considerable number of these studs is necessarily employed, with the result that, when it becomes necessary to change the packing for the ram, all these bolts must be unscrewed to 65 remove the ram for repacking. The operation of thus removing, repacking, and replacing the ram is necessarily, therefore, one which consumes considerable time, during which time, of course, the mill must be 70 stopped. In the best type of mills now employed, it may require a couple of hours' time to effect these operations, and on account of the unreliability of the packing, this may be required to be done two or three 75 times in a day. The resulting loss of time for operating the mill is serious, especially in view of the fact that cane crushing mills, to which reference is more particularly had, can only run for a limited season and loss 80 of time during that season is irreparable.

The present invention has for its object to produce an improved pressure regulating device for roller mills of such a character that the operation of replacing defective 85 packing may be expeditiously performed, thereby decreasing the loss of time incident to such operations.

With this and other objects not specifically referred to in view, the invention consists in certain constructions and in certain parts, improvements and combinations as will be hereinafter referred to and specifically pointed out.

Referring to the accompanying drawings: 95 Figure 1 illustrates in end elevation so much of a three roll roller mill as is necessary to an understanding of the invention. Fig. 2 is a plan view of the construction shown in Fig. 1, the hydraulic regulator indicated in 100 Fig. 1 being, however, omitted from this view. Fig. 3 is a sectional elevation, on an

- enlarged scale, of the pressure regulator construction shown in Fig. 1. Figs. 4 and 5 are sectional plan views, respectively, of the construction shown in Fig. 3, the planes of the sections being indicated by the lines 4—4 and 5—5, respectively, in said figure. Fig. 6 is a detail sectional view illustrating the interior construction of the bore of the cap shown in the preceding figures, showing the locking devices which may be employed. Fig. 7 is an exterior view of the cylinder shown in the preceding figures.
- Referring to the accompanying drawings which illustrate one embodiment of the invention, 1 indicates the side frames on which the mill construction is mounted, the housings in which the roll bearings are mounted being indicated at 2. The mill illustrated employs three rolls the journals of which are marked 4, 5 and 6, these rolls being intergeared, as usual in mill constructions. The bearings for the lower rolls are held in position by caps 7, 8, and the bearings for the upper roll are held in position by caps 9.
- Constructions embodying the invention will include pressure regulating devices by which the pressure developed by the rolls is substantially uniform notwithstanding variations in the amount of material passing between the rolls. These pressure regulating devices may coöperate with one or more of the rolls, as desired, but in the particular construction illustrated, the devices coöperate with the upper roll.
- As illustrated, the caps 9 are held in position on the housings by long bolts 10 which extend through the housings and through plates 11 located in recesses 12 in the frame 1, the lower ends of the bolts being provided with slots through which pass keys 13, as usual in such constructions. These bolts, as, shown, are provided with heavy nuts 14 which when turned down lock the caps securely to the housings.
- In constructions embodying the invention, each cap will be provided with an interior chamber or bore arranged to receive a cylinder which forms a part of the pressure regulating construction, the cylinder being removably located and firmly held in position in the bore or chamber of the cap. In the particular construction illustrated, the bore or chamber referred to is marked 15 and the cylinder is marked 16. While the construction by which the cylinder is locked in position in the bore of the cap may be varied, in the particular construction shown, the bore is provided with two locking projections 17 which may be formed integrally with the cap by the boring operations in a manner which will be readily understood. It is, of course, apparent that the locking devices employed should be extremely strong in order to withstand the pressures developed in the operation of the mill, and when they are

formed in the manner described the variation in the bores should be such as to provide strong heavy shoulders, the shoulders referred to being marked 18. The cylinder, in the bore construction illustrated, is provided with corresponding projections 19, these projections having shoulders 20, the projections being less in width than the spaces between the projections 17 in the bore. The cylinder may be provided with any suitable means for manipulating it, such, for instance, as eye bolts 21, fast in its head (see Figs. 1 and 2). With this construction it is apparent that the cylinder may, by means of a crane, or other suitable handling device, be dropped into the bore of the cap, the projections 19 passing between the projections 17 on the bore. The position which the lugs 19 occupy when the cylinder is being placed in position is indicated by dotted lines in Fig. 5. When the cylinder has been dropped into the bore it will be given a quarter turn so as to bring the shoulders 20 of the projections 19 underneath the shoulders 18 of the projections 17. Means may be provided for bringing the shoulders 20 firmly and snugly against the shoulders 18. While these means may be varied in character, as shown, the head of the cylinder 16 is provided with a threaded boss 22 engaged by a nut 23 sufficiently large to overlie the edge of the cap around the bore. This nut may be provided with openings, as 24, into which a bar may be inserted for the purpose of turning the nut. The cylinder is provided with the usual recess or chamber 25 to receive a ram, as 26, this ram, in the construction shown, bearing on a block 27 which in turn bears on the box 28 of the roll journal 5. The ram will be packed in the recess 25 of the cylinder by any suitable packing, such a packing being indicated at 29. This form of packing being well-known, a specific description of it is unnecessary. The cylinder will further be perforated, as at 30, to admit the fluid employed for operating the ram into the chamber 25, the pipe for admitting the fluid being indicated at 31 and being held in position by a suitable collar 32 and bolts 33.

If desired, means may be provided for holding the cylinder in such position that its locking devices will properly and truly engage with the locking devices in the cap, and these means may be of such character as to indicate when the cylinder is properly positioned in order to prevent the mill from being started before the locking engagement between the cylinder and the cap is established. In the construction shown, there are provided stop pins 34, 35, these pins being threaded through bosses 36 on the cap and extending into the bore or chamber of the cap below and in line with the adjacent edges of the projections 17. When the

cylinder is to be removed, one of these stop pins, say, the pin 35, is unscrewed, which will permit the cylinder to be turned toward the left, as shown in Fig. 4, the 5 movement being continued until one of the shoulders 20 strikes the other pin, 34, at which time the cylinder will be in position to be drawn out of the bore in the cap. When the cylinder is replaced, it is apparent 10 that the stop pin 35 cannot be screwed in until the cylinder has been properly positioned in the bore. So long as this pin is not screwed in, therefore, the operator is informed that the cylinder is not in its proper 15 position in the bore of the cap.

The pipe 31 will be arranged to connect with a suitable pressure regulator, 36'. The details of such regulators, ordinarily known as hydraulic regulators, are well-known and 20 a specific illustration and description of the one indicated is unnecessary.

It will be understood that a pressure regulating device of the character referred to will be employed at each end of the roll or 25 rolls to which it is applied, and that the piping will be so arranged that the regulator will connect with both cylinders.

It is apparent that with this construction a ram may be repacked very quickly. When 30 this operation is necessary, the nut 23 is loosened slightly and one of the pins 34, 35 unscrewed. The cylinder may then be lifted by a crane, or other lifting device, out of the cap and the repacking proceeded with, after 35 which the cylinder may be readily replaced. The two operations referred to require, of course, but very little time, so that the replacing of the packing can be very quickly performed. Further, if desired, spare 40 cylinders and rams, the packings of which have been thoroughly tested out, may be kept in the storehouse, and where a packing breaks down, another cylinder and ram may be substituted for the ones rendered useless by 45 the failure of the packing which will still further lessen the time during which the mill must be stopped to replace a packing.

Changes and variations may be made in the construction by which the invention is 50 carried into effect. The invention is not, therefore, to be confined to the particular construction herein described and illustrated in the accompanying drawings.

What is claimed is:—

55 1. A pressure regulating device for roller mills including in combination an interiorly bored cap for the roll support, a cylinder removably located in the bore of the cap, a ram in the cylinder operating on the roll 60 bearing, and fluid regulating means connected with the cylinder.

2. A pressure regulating device for roller mills including in combination an interiorly bored cap for the roll support, a cylinder located in the bore of the cap, locking means

carried by the cap, locking means on the cylinder which may be caused to engage with the locking means in the cap, and a ram in the cylinder for operating on the roll bearing. 70

3. A pressure regulating device for roller mills including in combination an interiorly bored cap for the roll support, a cylinder located in the bore of the cap, locking projections in said bore, locking projections on the cylinder which engage with the projection in the bore, and a ram in the cylinder for operating on the roll bearing. 75

4. A pressure regulating device for roller mills including in combination an interiorly bored cap for the support, locking projections in the bore, said projections being spaced apart circumferentially, a cylinder located in the bore of the cap, locking projections on the cylinder less in width than the 80 space between the projections in the bore and arranged to coöperate with said projections, and a ram in the cylinder for operating on the roll bearing. 85

5. A pressure regulating device for roller mills including in combination an interiorly bored cap, bolts for securing the cap to the roll support, locking projections in the bore, a cylinder located in the bore, locking projections on the cylinder which may be caused 90 to engage with the projections in the bore, means for bringing the projections on the cylinder snugly against the projections in the bore, and a ram in the cylinder operating 95 on the roll bearing. 100

6. A pressure regulating device for roller mills including in combination an interiorly bored cap for the roll support, locking projections in the bore, said projections being spaced apart circumferentially, a cylinder 105 in the bore having locking projections less in width than the spaces between the projections in the bore, a threaded boss on the cylinder, a nut on the boss, said nut overlying the cap whereby the locking projections in the bore and on the cylinder may be brought 110 snugly together, a ram in the cylinder for operating on the roll bearing.

7. A pressure regulating device for roller mills including in combination an interiorly 115 bored cap for the roll support, locking means carried by the cap, a cylinder located in the bore of the cap, locking means on the cylinder which may be caused to engage with the locking means of the cap, means 120 for determining when said locking means are properly engaged, and a ram in the cylinder for operating on the roller bearing.

8. A pressure regulating device for roller mills including in combination an interiorly 125 bored cap for the roll support, locking projections in the bore of the cap, said projections being spaced apart circumferentially, a cylinder in the bore of the cap, locking projections on the cylinder less in width than 130

the spaces between the projections in the bore and arranged to coöperate with said projections, means for determining when said projections are properly engaged, and
5 a ram in the cylinder operating on the roll bearing.

In testimony whereof, I have hereunto set

my hand, in the presence of two subscribing witnesses.

DAVID R. BOWEN.
